Application filed June 21, 1892. Serial No. 437,521. Term of patent 3½ years.

To all whom it may concern:

Be it known that I, CHARLES L. DEPOLLIER, a citizen of the United States, residing in Brooklyn, in the county of Kings and State 5 of New York, have invented and produced a new and original Design for Watch-Cases, of which the following is a specification, reference being had to the accompanying drawing, forming part thereof, and which shows my 10 design on a watch-case in side elevation.

The leading features of my design consist in the representation of an eagle A, having outspread wings and perched upon a globe B, from which latter radiate two American flags

C. Back of the globe and back of the eagle 15 is represented a wreath D, the whole being assembled or arranged as shown in the drawing.

Having fully described my invention, what I claim as new, and desire to secure by Letters Patent, is—

The design for a watch-case, as herein shown and described.
